RACE TRACK SCARIFIER

Donald McDonald, Sacramento, Calif., assignor to
Georgia S. Cusack, Sacramento, Calif.

Application July 15, 1950, Serial No. 173,980

9 Claims. (Cl. 55—128)

This invention relates to scarifiers, and particularly to one primarily designed for scarifying or re-finishing race tracks, which need reconditioning every so often, and which operation to be satisfactory requires a top-ground layer of even density and depth throughout the extent of the track.

One of the major objects of my invention, therefore, is to provide an implement for the purpose so constructed that the entire track surface in the path of movement of the implement will be worked over and scarified to the same depth, and such depth may be regulated to an extreme nicety as is desirable.

A further object is to provide a scarifier which, while covering a wide area when in operation so that the number of passes necessary to work over a track from side to side is reduced to a minimum, may be greatly reduced in width by a simple power controlled operation so that the machine is then capable of passing through a road gate and moved along a highway without then occupying an excessive portion of the highway.

A further object is to provide, as a valuable adjunct to the scarifying operations, a leveler unit adapted to be mounted in trailing relation with the scarifier and arranged to properly level the scarified dirt when this is desired, so that scarifying and leveling are then carried out at one operation.

A further object is to provide a machine for the purpose which is extremely efficient and fast in operation, and which is rugged and inflexible so that the scarifying elements, when once set for a certain depth, will be maintained at that depth without deviation.

A further object of the invention is to provide a practical and reliable race track scarifier, and one which will be exceedingly effective for the purpose for which it is designed.

These objects are accomplished by means of such structure and relative arrangement of parts as will fully appear by a perusal of the following specification and claims.

In the drawings:

Fig. 1 is a top plan view of the implement in its maximum-width working position.

Fig. 2 is a top plan view, somewhat diagrammatic, of the implement folded for transportation.

Fig. 3 is a side elevation of the machine in working position.

Fig. 4 is an enlarged fragmentary longitudinal section on line 4—4 of Fig. 2.

Fig. 4 is an enlarged fragmentary transverse section on line 5—5 of Fig. 1.

Fig. 6 is an enlarged fragmentary cross section on line 6—6 of Fig. 1.

Fig. 7 is a similar view on line 7—7 of Fig. 1.

Fig. 8 is a fragmentary longitudinal section on line 8—8 of Fig. 1.

Fig. 9 is a top plan view of a finish leveler unit attached to and designed to cooperate with the scarifier.

Fig. 10 is an enlarged side view of the swivel mount of the leveler, detached from the scarifier.

Fig. 11 is a top plan view of the swivel mount, detached from the leveler.

Fig. 12 is an enlarged side view of one of the adjustable wheel mounts of the leveler.

Referring now more particularly to the characters of reference on the drawings, the machine comprises upper and lower frame units indicated generally at 1 and 2, of substantially the same size and construction, and

2

when the machine is in operation, forming a V with the apex forwardly.

The upper frame unit comprises side beams 3 and 4 of hollow box-like form, beam 3 extending ahead of beam 4 to form the actual apex of the unit; beam 4 at its forward end terminating adjacent the inner face of beam 3. The lower frame unit 2 similarly comprises hollow side beams 5, symmetrical to the corresponding upper beams 3 and 4 and disposed directly below the same.

Overlapping pairs of bracket plates 6 project laterally from the inner faces of beams 3 and 4 and similar brackets 7 project from beams 5 just behind the apex of the frame units. An upstanding king pin 8 slidably and turnably projects through these brackets and through brackets 9 which straddle brackets 7 (see Fig. 4) and which are mounted on the forward side of the upstanding leg 10 of a gooseneck 11. This gooseneck extends over and ahead of the frame units to supported swivel connection with a wheeled pony truck 12 to which a draft tongue 13 is rigidly connected.

The pin 8 is secured to the lower bracket 9 and to the top member of the gooseneck; said member clearing the upper frame unit 1 sufficiently to allow of vertical movement of said unit 1 relative to unit 2. Said unit 2, by reason of the engagement of the gooseneck brackets 9 with brackets 7, is held at a fixed level.

In order to maintain the gooseneck against relative lateral swinging about the king pin when the machine is in operation, a rigid post 14 depends from the gooseneck on the side nearest beam 4, on the lower end of which post is a projecting lug 15 which fits in the space between the side beams 5 of the lower frame unit 2.

Rigid stub axles 16 project outwardly from the side beams 5 intermediate their ends, which support wheels 17 turnable about vertical king pins 18. Arms 19 project forwardly from suitable connection with the wheels adjacent their king pins, which arms are connected to hydraulic rams 20 extending thence to beams 5 so that the wheels may be set parallel to the line of travel irrespective of the angular relation of the frame units to such line. When the frame units are set in working position, the wheels are laterally inward of the rear ends of the side beams of such units.

The scarifying elements of the machine are rectangular vertical blades 21 removably bolted to brackets 22 secured on the underside of the beams 3 and 4 in spaced relation throughout the length thereof. The blades depend thence through the beams 5, at the bottom of which said blades slidably pass between guides 23 on said beams.

The brackets 22 and guides 23, in addition to serving their main purpose, also form the connecting elements for the side members of the beams at the bottom of said members; the latter being connected together at the top by cross plates 24.

The blades 21, for each beam, are parallel to each other, but are diagonal to the longitudinal plane of the beams in a direction opposite to the angle of the opposed beams relative to each other, and are also diagonal to the direction of travel of the machine. The spacing of the blades relative to their width is such that there is no gap between the blades in the direction of travel, and thus all the ground area between the widely separated rear ends of the frame beams is engaged and scarified as the machine moves forward. This complete ground coverage extends across the apex of the frame unit without any special blade re-arranging due to the fact that beam 3, and the corresponding beam 5 below, extends across the apical line and can thus carry a pair of blades extending diagonally across said line.

In order to raise or lower frame unit 1 so as to alter the depth of penetration of blades 21 into the ground, or lift them entirely clear for transportation, hydraulic rams 25 extends between cross members 26 and 27 on the beams of frame units 1 and 2, respectively (see Fig. 7) at suitably spaced intervals between adjacent scarifier blades and without having to alter the spacing of such blades.

The frame unit 1 is guided during vertical movement not only on king pin 8, but on other heavy pins 28 dis-

posed adjacent but laterally inward of the frame units, preferably opposite the wheel supporting axles 16, and mounted in connection with pairs of brackets 29 and 30 projecting from frame units 1 and 2, respectively (see Fig. 5). The pins are secured with brackets 30, but relatively slide through brackets 29.

In order to adjustably limit the downward movement of frame unit 1, and the scarifier blades so that the latter may be set to penetrate the ground to any exact depth desired, heavy-duty hand-turned vertical stop screws 31 are threaded through cross members 32 on beams 3 and 4 at intervals, and at their lower end engage cross stop plates 33 on the lower beams 5 (see Fig. 6). To determine the adjusted position of the stop screws for any desired depth penetration of blades 21, graduated gauge bars 34 upstand from the side of beams 5 adjacent the stop screws, and slide through pointer-forming collars 35 on the corresponding beams 3 and 4. As will be obvious, this arrangement, while positively limiting the downward movement of the frame unit 1, does not interfere with full raising of said unit so that the blades may be lifted clear of the ground when desired in maneuvering the machine while assuring that the blades will return to the originally set depth when the frame unit is again lowered.

In order to collapse the frame units when the machine is to be transported, as well as to maintain them at the proper angle of separation when the machine is in operation, heavy toggle link units 36 and 37 extend between the pairs of brackets 29 of frame unit 1 and the pairs of brackets 30 of frame unit 2, respectively; said link units turning on pins 28 (see Fig. 5). Said link units include a central upstanding pivot pin 38 fixed with the lower link unit but on which the upper link unit may slide as well as turn.

To extend or collapse the toggle links, so as to separate or pull the frame units together, said units turning about king pin 8 as an axis, the following arrangement is provided:

Pivoted on a bracket 39 projecting rearwardly from the back of gooseneck 11 is a bell crank lever 40, to the upper end of which one end of a hydraulic ram 41 is connected, the other end of the ram being mounted on the gooseneck. The lower end of the lever 40 is connected by a link 42 to the pin 38 just above frame unit 2 (see Fig. 4).

When the frame units and toggle links are fully collapsed, as shown in Fig. 2, said units lie parallel to each other with brackets 29 and 30 abutting. At the same time, wheel control rams 20 are actuated to position the wheels parallel to the frame units. The wheels may then be locked in that position by pins 43 placed through holes in arms 19 and matching holes in rigid brackets 44 projecting outwardly from beams 5 and which are then engaged by said arms as shown in Fig. 2.

It will, of course, be understood that a power unit is provided to supply hydraulic pressure for the operation of the various rams, such unit being mounted on the gooseneck and enclosed for protection within a hood H.

The operator's seat 45 is also mounted on the gooseneck, such operator controlling the functioning of the various rams as may be required by means of valve control levers 46 mounted as a unit in connection with the hood in front of and convenient to the seat.

With the wide scarifier blades, and with such blades on the angled frames sloping in opposite directions away from the apex of said frames, a relatively high central windrow of dirt is formed in line with and back of the apex, while the rearmost blades dig definite troughs in the ground.

In order to both level out this windrow and fill the troughs with one pass of the implement when a finish-level effect is desired, as on a race track, a leveler unit is provided as a removable attachment to the scarifier.

This leveler comprises a pair of side beams 47 having smooth upstanding outer faces, and extending in rigid diverging relation to each other from a forward central junction or apex 48 to a rearward termination at least as far apart as the rearmost blades 21 of the scarifier, as shown in Fig. 9.

At their forward end, the beams 47 are tied by a top bearing bracket 49 which supports a horizontal longitudinally extending swivel pin 50. Ahead of the bracket, the pin is formed with a transverse fork 51 straddling a lug 52 projecting rearwardly from a vertical sleeve 53,

the lug and fork being pivoted together by a transverse pin 54.

The sleeve 53 slides and turns on a vertical pin 55 secured to a bracket 56. This bracket is mounted on a cross beam 57 adapted to extend between the side beams 5 of the lower scarifier frame 2 just rearwardly of the toggle linkage 37 of said frame 2, as shown in Fig. 9 and to be removably secured to said frame by bolting the same to plates 58 thereon. With this arrangement, it will be seen that the leveler may swing up or down longitudinally about pin 54, and laterally about pin 50, and may also rotate about pin 55, so that the mounting unit above described is in effect a universal joint.

In order to raise or lower the front end of the leveler 15 relative to the fixed-level beam 57, a screw 59, parallel to pin 55, upstands from lug 52 in which it is turnably fixed, and is engaged by a nut 60 confined by a yoke 61 mounted for rotation on pin 55 and held against vertical movement between the upper bearing plate 62 of pin 55 20 and a collar 63 on said pin above the yoke.

The leveler, at its rear end, is supported by rear wheels 64 mounted on a rigid transverse axle 65 above beams 47 and riding in the troughs 66 formed by the rearmost scarifier blades 21.

25 The axle is engaged by upstanding guides 67 on the beams 47 and each of the latter is floatably and adjustably suspended from the adjacent portion of said axle by a substantially horizontal lever 68 pivoted intermediate its ends on links 69 mounted on and upstanding from 30 the axle in straddling relation to the adjacent guide 67. At one end, the lever is connected to an arm unit 70 upstanding from the adjacent beam 47, and suitable pull-down means is applied to the other end of the lever, such as a ram 71 mounted on the axle. Piping 72 for 35 the rams extends along the beams 47 to the cross beam 57, where detachable connection is made with the source of pressure and with the necessary control valves mounted adjacent valve levers 46 for independent actuation by the operator.

40 The above described leveler-frame rear-end suspension arrangement enables either frame to be raised or lowered at such end, as the particular conditions may require to give the best leveling results.

In order to prevent undue lateral swiveling of the 45 leveler, should wheels 64 not be riding in well-defined troughs, slack chains 73 are connected between frames 67 intermediate their ends and the scarifier frame 1 at its rear ends.

When the scarifier is to be collapsed for transportation, the cross beam 57 is unbolted, the chains 73 detached, and the ram piping connections uncoupled, thus freeing the leveler from any connection with the scarifier.

From the foregoing description it will be readily seen that there has been produced such a device as substantially fulfills the objects of the invention, as set forth herein.

While this specification sets forth in detail the present and preferred construction of such device, still in practice such deviations from such detail may be resorted to as 50 do not form a departure from the spirit of the invention, as defined by the appended claims.

I claim:

1. A scarifier comprising symmetrical upper and lower frame units each including side members disposed one 55 above the other, a king pin pivoting the frame units together at their forward end for movement of the side members between divergent and substantially parallel folded positions while allowing of vertical movement of the upper frame unit relative to the lower frame unit, 60 guide means between the side members intermediate their ends for guiding the upper side members as they move up or down, rams between the side members for imparting upward movement to said upper members, scarifier blades mounted on the upper members and depending below the 65 lower side members for ground engagement, rear wheels supporting the lower side members, a rigid gooseneck extending forwardly over the frame units in clearance relation to the upper unit, a steerable draft truck supporting the 70 forward end of the gooseneck, and means applied to the side members to move the same between such divergent and folded positions at will.

2. A scarifier as in claim 1, in which said guide means 75 comprises upstanding guide pins fixed on the lower side members and spaced brackets on the upper side members

through which the pins slidably project, and said last named means includes upper and lower toggle-link units mounted at their ends on said guide pins, the upper link unit being retained between said brackets for vertical movement with said upper side members, a central pin connecting the toggle link units, said pin being secured on the lower unit and relatively slidable through the upper unit, and power means mounted on the gooseneck and connected to said central pin between the toggle link units to extend and collapse the latter.

3. A scarifier as in claim 1, with means between the frame units and the gooseneck to prevent relative rotation therebetween about the king pin as an axis when the frame units are in a divergent position.

4. A scarifier comprising a frame structure which includes side members, scarifier elements depending from the members, means pivoting said members together adjacent their forward end for relative folding movement in a horizontal plane from an operative rearwardly divergent position, said means including a vertical king pin, a forwardly projecting draft member supporting said king pin, and locking means between said draft member and the frame structure preventing lateral swinging movement of the draft member relative to the frame structure when the side members of said structure are in said operative position.

5. A scarifier as in claim 4, in which said draft member overhangs the frame structure and the side members abut against each other ahead of the king pin when said members are in operative position to then provide a horizontal forwardly opening socket therebetween; said locking means comprising a post rigid with and depending from the draft member ahead of the socket, and a rearwardly projecting lug on the lower end of the post in position to enter the socket.

6. A scarifier comprising a lower wheel-supported frame unit including side members, an upper blade-mounting frame unit including side members overlying the members of the lower unit, means guiding the upper unit for vertical movement relative to the lower unit and including a king pin pivoting the units together adjacent their forward ends to permit relative swinging of the units in a horizontal plane about said king pin, a power device mounted in connection with one frame unit, and actuating means between said device and both units and including said guide means to swing the side members of both units simultaneously.

7. A scarifier as in claim 6, with power devices connected between the upper and lower frame units to move the upper unit relative to the lower unit without affecting the operation of said actuating means.

8. A scarifier as in claim 6, in which said guide means includes upstanding guide pins fixed in the side members of the lower unit and slidable through the members of the upper unit; said actuating means comprising upper and lower transversely foldable toggle link units extending between and engaging said guide pins, means retaining the toggle units in unchanged horizontal relation with the respective frame units regardless of relative vertical movement of the latter, a central pin connected and fixed with one toggle unit and slidable through the other, and a push-pull link connected to said central pin between the upper and lower toggle units and to which said power device is connected.

9. A scarifier comprising a frame structure which includes side units each having an upper and a lower member, scarifier elements depending from the upper members; means pivoting said units together adjacent their forward end for relative folding movement in a horizontal plane from an operative rearwardly divergent position, means mounting the frame structure for movement along the ground and including elements projecting outwardly from and rigid with the lower members of said side units, rear wheels outwardly of said elements, wheel mounting means supporting the wheels from said elements for swivel movement about vertical axes, arms rigid with and projecting forwardly from said wheel mounting means, and power rams extending between the forward end of said arms and the side units ahead of the wheels.
